F. D. COPPOCK

CONCRETE CROSSING SLAB

Filed Oct. 24, 1927

INVENTOR.
Fred D. Coppock

BY
Geo. F. Himmel
ATTORNEY.

UNITED STATES PATENT OFFICE.

FRED D. COPPOCK, OF GREENVILLE, OHIO.

CONCRETE CROSSING SLAB.

Application filed October 24, 1927. Serial No. 228,427.

This invention relates to railway crossings, and has for its object to provide, in a manner as hereinafter set forth, a crossing of such class with spacer means for maintaining crossing slabs an appropriate distance from the track rails and further with means for expeditiously anchoring the crossing slabs to the spacer means.

A further object of the invention is to provide, in a manner as hereinafter set forth, a railroad crossing including armored, reinforced crossing slabs, spacer means between the slabs and track rails, and means interengaging with the spacer means and slabs for anchoring these latter to the former.

Further objects of the invention are to provide, in a manner as hereinafter set forth, a railroad crossing which is strong, durable, compact, conveniently installed with respect to the track rails, thoroughly efficient in its use, and comparatively inexpensive to set up.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a fragmentary view, in cross section, of a railway crossing in accordance with this invention.

Figure 2 is a fragmentary view, in top plan and broken away, of a railway crossing in accordance with this invention.

Figure 3 is a top plan view of one of the crossing slabs.

Figure 4 is a side view thereof.

A railway crossing, in accordance with this invention, includes courses of armored, reinforced crossing slabs, filler elements between the track rails and the courses of the slabs arranged adjacent to the track rails, shims mounted on the ties for supporting the crossing slabs, and anchoring elements between the filler elements and said adjacent courses of the slabs and with the anchoring elements interengaging with the filler elements and with the slabs of such adjacent courses thereof.

A pair of filler elements is employed in connection with each track rail and act as spacing means between the slabs of the pair of courses of the slabs which are arranged adjacent to such track rail, but only one track rail and one pair of filler elements is illustrated. One of the filler elements is indicated at 1 and the other at 2 and each of said elements is of a length to correspond to the length of a course of the crossing slabs. The filler element 1 has its upper face concaved as indicated at 3 and the concavity extends from one end to the other end of such element. The upper face of the element 1 is furthermore provided with a beveled portion 4. The sides and bottom of the element 1 are squared. The element 1 is of less height than the element 2 and the latter has its inner side, at the upper portion thereof mortised to form an inclined abutment 5 and a beveled seat 6, the inclination of the abutment 5 being towards a side of the head 7 of the track rail 8. The seats 4 and 6 conform in contour to the contour of the lower face of the head 7 of the rail 8. The filler elements 1 and 2 abut against the points of joinder between the web of the rail 8 and the head 7 of the latter and said filler elements further abut against the points of joinder between the web of the rail 8 and the base 9 of the latter. The upper face of the element 1 is arranged below the head 7 of the track rail and the upper face of the element 2 is positioned in close proximity to the tread of the head 7.

Mounted on the tie 10 is a rail chair 11, upon which is mounted the base 9 of the rail 8 and spikes 12 are employed for securing the rail 8, chair 11 and tie 10 together. The chair 11 is provided with openings 13 for the passage of the spikes 12. The width of the element 1 is such that when such element is mounted in position as shown in Figure 1 it does not project beyond one end of the chair 11. The width of the element 2 is such that when mounted in position it projects beyond the other end of the chair 11, see Figure 1.

The slabs of the courses which are arranged adjacent to the track rail 8 are indicated at 14, 15. The slabs 14 and 15 are mounted on shims 16 positioned upon the ties 10. The shims 16 are constructed of wood. The elements 1 and 2 are constructed of wood and preferably are creo-

soted. The element 1 is provided with a series of spaced, transversely extending sockets 17 which open at the outer side thereof and the element 2 is formed with a series of spaced, transversely extending sockets 18 which open at the outer side thereof. The sockets are so arranged that three will be associated with a slab 14 or a slab 15. Secured in each of said sockets is an anchoring element in the form of a pin 19 and which is of a length to project a substantial distance laterally from a filler element. The pins 19 are fixedly secured in the filler elements 1, 2 and engage the sockets in such elements throughout. The pins are so set up, preferably, that one half will be anchored in the fillers and the other half will project laterally from the filler elements. The shims 16, preferably are of less height than the height of the rail seat 11.

Each of the crossing slabs has its upper portion armored and each is furthermore provided with reinforcements throughout, and said reinforcements are disposed horizontally and longitudinally with respect to the body of the slab, and the latter is formed from concrete.

The body of each slab is indicated at 19', is of rectangular contour and of a height greater than the height of the filler element 2. Surrounding the upper portion of the body 19' is a rectangular, metallic frame 20 which constitutes an armor and the outer face of said frame 20 is flush with the outer face of the upper portion of the body 19'. The longitudinally extending reinforcements for the body 19' consist of metallic rods 21 which are preferably cylindrical in cross section and the horizontal reinforcements consist of rods 22 of cylindrical cross section. The longitudinal reinforcing rods are arranged in sets, one set positioned between the center and upper face of the body 19' and the other set between the center and lower face of the body 19'. The horizontally disposed reinforcements are also arranged in sets and one set is positioned above the upper set of the longitudinal reinforcements and the other set of the horizontal reinforcements is arranged below the lower longitudinal set. Preferably the horizontal reinforcements abut against the longitudinal reinforcements. The upper horizontal reinforcements have down turned ends 23 which engage in loops 24 struck from the sides of the frame 20. The longitudinal reinforcements are of a length slightly less than the length of the body 19'.

Each slab 14, as well as each slab 15, these slabs forming the courses arranged adjacent to the track rail 8, have their inner sides, below the frame 20 formed with a series of sockets 25 which gradually decrease in diameter from the outer to the inner ends

thereof, or in other words each socket 25 is tapered and is adapted to receive the laterally projected portion of an anchoring pin 19. The pins 19 are constructed of steel and have a wedge-like engagement with the sockets 25 so as to anchor the slabs 14 and 15 to the filler elements 1 and 2 respectively. The sockets in a slab 14 or 15 are arranged in spaced relation similar to the spaced relation of the sockets in the filler elements 75 whereby when the slabs 14 and 15 are set up the sockets in these slabs will oppose the sockets in the filler elements. As illustrated in Figure 4, the inner side of a slab 14 or 15 is provided with three sockets 25.

The frame 20 provides an armor for the upper part of the body portion 19' and each side, as well as each end of said frame has a squared outer face, but its inner face from a point removed from the center thereof inclining inwardly as at 26, 27 so as to overlap a part of the body portion 19' and secure the frame 20 to said body portion 19'. The setting up of the inner face of the sides and ends of the frame 20 with the inclined portions forms broad edges for said sides and ends. The lower longitudinal set of reinforcing bars, as well as the lower horizontal set of reinforcing bars are arranged below the sockets 25 formed in the body portion 19'. The lower portion of the side of each body portion 19' can be beveled, if desired as indicated at 28. The armoring and reinforcing of the upper part of the body portion 19' increases the life thereof.

What I claim is:

1. In a railway crossing a pair of filler elements for juxtaposition with respect to the sides of a track rail, a course of crossing slabs abutting against each of said elements, each of said elements corresponding in length to the length of a slab, and means carried by said filler elements and extending into the slabs of said courses for anchoring said slabs in position and in abutting engagement with respect to said elements.

2. In a railway crossing a pair of filler elements for juxtaposition with respect to the sides of a track rail, a course of crossing slabs abutting against each of said elements, each of said elements corresponding in length to the length of a slab, and means carried by said filler elements and extending into the slabs of said courses for anchoring said slabs in position and in abutting engagement with respect to said elements, one of said elements of less height than the other and each of said elements abutting against the track rail and further extending below and abutting against the lower face of the tread of the rail.

3. In a railway crossing, a filler element adapted to be positioned adjacent a track rail, and an armored, reinforced crossing slab having its inner side formed with a plu-

rality of spaced sockets for the reception of anchoring means to couple the slab with the filler element.

4. In a railway crossing, a filler element 5 adapted to be positioned adjacent a track rail, and a reinforced concrete slab having the upper part of its body portion encompassed by a metallic frame to constitute an armor therefor, said body portion on one 10 side thereof and below said frame formed with a plurality of spaced sockets for the reception of anchoring means to secure said slab to the filler element.
5. In a railway crossing a pair of filler 15 elements for juxta-position with respect to the sides of a track rail, reinforced concrete slabs positioned against each of said filler elements, each of said slabs having the upper part of its body portion encompassed by a 20 metallic frame to constitute an armor therefor, each of said elements having its outer side formed with a series of spaced sockets, each of the slabs of each of said courses having its outer side provided with a plurality of 25 spaced sockets arranged below said frame, and pins secured in the sockets of said elements and extending into the sockets of said slabs for anchoring these latter in position.
6. In a railway crossing a pair of filler 30 elements for juxta-position with respect to the sides of a track rail, reinforced concrete slabs positioned against each of said filler elements, each of said slabs having the upper part of its body portion encompassed by a 35 metallic frame to constitute an armor therefor, each of said elements having its outer side formed with a series of spaced sockets, each of the slabs of each of said courses having its outer side provided with a plurality of 40 spaced sockets arranged below said frame, and pins secured in the sockets of said elements and extending into the sockets of

of said slabs for anchoring these latter in position, each of the sockets of each of said slabs being tapered.

7. In a railway crossing a pair of filler elements for juxta-position with respect to the sides of a track rail, reinforced concrete slabs positioned against each of said filler elements, each of said slabs having the upper 45 part of its body portion encompassed by a metallic frame to constitute an armor therefor, each of said elements having its outer side formed with a series of spaced sockets, each of the slabs of each of said courses 50 having its outer side provided with a plurality of spaced sockets arranged below said frame, and pins secured in the sockets of said elements and extending into the sockets of said slabs for anchoring these latter in 55 position, each of the sockets of each of said slabs being tapered, said slabs of greater heights than said filler elements, one of said filler elements being of greater height than the other, and each of said filler elements 60 abutting against one side of the lower face of the tread of the track rail.

8. In a railway crossing, a filler element adapted to be positioned adjacent a track rail, a crossing slab consisting of a concrete 70 body having oppositely extending reinforcements near the top and near the bottom thereof, a metallic frame encompassing the upper part of said body portion and providing an armor therefor, said frame flush with 75 the top of said body portion, said body portion further provided on one side thereof with a series of spaced tapered sockets adapted to receive anchoring means for connecting said body portion to the filler element. 80

In testimony whereof, I affix my signature hereto.

FRED D. COPPOCK.
